United States Patent Office.

G. W. GAIL, OF BALTIMORE, MARYLAND.

Letters Patent No. 73,794, dated January 28, 1868.

IMPROVEMENT IN BAGS FOR PACKING TOBACCO.

The Schedule referred to in these Letters Patent and making part of the same.

TO ALL WHOM IT MAY CONCERN:

Be it known that I, G. W. GAIL, of Baltimore city, in the State of Maryland, have invented certain new and useful Improvements in Bags for Packing Tobacco; and that I do hereby declare that the following is a full, clear, and exact description thereof, reference being had to the accompanying drawings, and to the letters of reference marked thereon, which form a part of this specification, in which—

Figure 1 is a perspective of my tobacco-bag, showing the manner of folding the sides, also the flap thus formed, and the cord for securing the same.

Figure 2 is also a perspective, exhibiting the manner in which the mouth of the bag is closed and the flap secured.

The object of this invention is to provide an expeditious, economical, and, withal, an ornamental, method of packing tobacco for the market; and the nature of it consists in folding the sides of my bag in such a way that a flap will be formed, which, in connection with the folds, will entirely close its mouth when the cord which is attached to said flap is passed around the centre of the bag and secured, as indicated in fig. 2.

To enable others to enjoy the benefits of this invention, I will now describe its peculiarities.

A represents the bag, made in the usual way, to which is attached the cord d. After the bag is filled with tobacco, all the sides are folded except the one to which the cord is attached, as seen in fig. 1. The flap is now folded over the mouth of the bag, and the cord passed around its centre, and its end secured by being passed around its opposite end several times, or in any other convenient method.

What I desire to secure by Letters Patent is—

A bag for packing tobacco, when folded as described, and secured by means of a cord passing around its centre, substantially in the manner as set forth.

In testimony that I claim the foregoing as my own, I affix my signature in presence of two witnesses.

G. W. GAIL.

Witnesses:

Wm. McKinlee,

Jos. J. Stewart.
